UNITED STATES PATENT OFFICE

ROBERT HENRY COLLEN, OF EAST HAM, ENGLAND, ASSIGNOR OF ONE-HALF TO JOHN BROADWOOD & SONS LIMITED, OF LONDON, ENGLAND

PNEUMATICALLY-OPERATED PLAYER MECHANISM FOR MUSICAL INSTRUMENTS

Application filed July 24, 1928, Serial No. 295,052, and in Great Britain February 24, 1928.

This invention relates to pneumatically operated player mechanism for musical instruments (hereinafter referred to as pianofortes) in which each note is operated by a striking motor, or bellows, when the latter is exhausted of air by the rarefaction of air in a wind chest, through the medium of a valvular device (under the influence of a diaphragm) secured to one side of a main suction board, to the other side of which is usually secured the said striking motor, or bellows, communication between the interiors of the said valvular device and the said striking motor, or bellows and between the interior of the said valvular device and the suction channel in the said main suction board, respectively, being effected by suitably arranged ducts, or passages. As the number of valvular devices and striking motors or bellows necessary to operate all the notes of an ordinary pianoforte is such that space will not permit of their being arranged in single rows, that is, a single row of valvular devices and a single row of striking motors, or bellows, it is the common practice to arrange these in two or more rows, that is, two or more rows of valvular devices each row of which is secured to a separate suction board, and two or more rows of striking motors, or bellows, usually secured to the other side of the said boards.

This invention has for its object to provide valvular devices which are so adapted that they can be mounted in two rows on one main suction board having only one suction channel and also so adapted that they can be quickly and easily attached to and detached from the said main suction board so that access can be readily had to the diaphragm and purse pockets and also to the passages in the said main suction board. The valvular devices are made, or mainly made, of metal or of material which can be easily cast or moulded and are so constructed that the valves therein can be more easily removed and replaced than hitherto.

According to this invention the valvular devices consist in or comprise a number of valve blocks, each of which has two or more valve chambers cast, or otherwise formed

therein, the inner ends of which open into a hollow, or cavity, formed in its under, or rear, side and having ducts, also cast, or otherwise formed therein, by which communication is effected between the respective valve chambers and passages in the suction board.

The valve blocks, are of relatively narrow width and are secured, in close proximity to each other, to the suction board in such position relatively to the pouch chambers that the hollow or cavity in each valve block, constitutes in conjunction with the member in which the said pockets are formed, a chamber by which communication between the suction channel and either of the valve chambers in each valve block, can be effected. The pouch chambers may be formed in a piece secured to and removable with the valve block.

In players in which it is required to employ both primary and secondary valvular devices the primary valvular devices may be arranged on an auxiliary suction board and the secondary valvular devices may be on the main suction board. I will more particularly describe this invention with reference to the accompanying drawing in which Figure 1 shows in transverse section a main suction board provided with secondary valvular devices in accordance therewith. Figure 2 shows in plan, a number of the said valvular devices secured in position relatively to each other to the said suction board, and Figure 3 shows in transverse section an auxiliary suction board provided with primary valvular devices.

Referring more particularly to Figure 1, 1 indicates the main suction board, 2 the suction channel, 3 the passages therein leading from a valvular device 4 to the striking bellows, or motors, 5 to which are connected the actuating mechanism 6 which operates the action proper of the instrument. In the arrangement shown the pouch chambers 7 are formed in a piece 8 interposed between the valvular piece 4, and the suction board 1, the said pouch chambers being shown communicating with tubes 9 leading to the tracker bar (not shown) or to the primary valvular device shown in Figure 3 by means of a port 10 opening into a cavity 11 in the underside of 100

the said piece 8 with which passages 12 leading to the said tubes communicate.

The whole of the pouch chambers 7 are arranged in two suitably spaced rows longitudinally of the main suction board 1 and in the arrangement shown a valvular device 4 is adapted to control the ducts or passages, ap-

pertaining to two pouch chambers.

Each valvular device comprises a valve block 4, having two valve chambers 13 cast, or otherwise formed therein, the inner ends of which open into a hollow, or cavity 14, formed in its under side and having ducts 15 also cast, or otherwise formed therein, by which communication is effected between the respective valve chambers and the passages 3 leading to the striking motors, or bellows 5. Communication between the hollow, or cavity, 14 and the main suction channel 2 is effected by a passage 16 in the piece 8 in which the pouch chambers 7 are formed. The hollow, or cavity, 14 in each base-piece or block constitutes, in conjunction with the piece 8, a chamber by which communication between the main suction channel 2 and either of the valve chambers 13 is effected.

The piece 8 in which the pouch chambers 7 are formed and the valve block 4 are secured together by screws 17 and both are secured to the main suction board 1 by screws 18 passed through holes formed in the said pieces at or towards the ends thereof and by a central screw, or post, 19 passed through a hole in the said valve block 4 midway of the valve chambers 13 and through the passage 16 in the said piece 8. The upper end of the screw or post 19 is screw-threaded and is provided with a nut 20 which acts to clamp the said parts to the suction board 1.

Within each of the valve chambers 13 is a double-acting valve 21, of the known kind, which controls ports 22 and 23 by which communication is alternately effected between the said valve chamber and the interconnecting hollow or cavity 14 in the valve block 4 and between the said valve chamber and the atmosphere. The double-acting valve 21 is provided with a stem 24, the inner end of which abuts against and is actuated by a diaphragm 25 secured to the piece 8 in which the pouch chambers 7 are formed. The port 22 through which atmospheric air is admitted into the respective valve chambers 13 is shown formed in a cap-piece 26 removably held on, or in, the open outer end of the valve chamber and having a central boss through which the outer end of the valve stem 24 passes and constitutes a guide therefor. The inner end of the valve stem 24 is guided in a spider formed in the port 23 at the inner end of the valve chamber 13. The construction and arrangement of the double-acting valves 21 are such that by removing the cap-piece 26 from the outer end of a valve chamber the said valve

valve chamber for inspection, or repair, and be replaced with facility. The cap-pieces 26 may be held in position on the outer ends of the valve chamber by a bridge-piece 27 slideable on the before mentioned central screw, or post 19 and held in position thereon by a nut 28. To remove a cap-piece 26 it is only necessary to unscrew the nut 28 to permit the ends of the bridge-piece 27 being raised clear of the outer ends of the stems 24 so that the said bridge-piece can be turned out of the path of the cap-pieces whereupon either or both can be removed and access to the double-acting valves 21 be had. Bleed holes 29 are provided through which air in the pouch chambers and interconnecting passages between the pouch chambers and the tracker bar is exhausted.

The primary valvular device shown in Figure 3 is substantially the same as the secondary valvular device shown in Figure 1. These valvular devices are mounted on an auxiliary suction board 1^a, secured to any suitable part of the instrument, in a similar manner to the valvular devices shown in Figures 1 and 2. The parts shown in Figure 3 corresponding to the parts shown in Figures 1 and 2 are marked with the same numerals of reference with the addition thereof of the index letter ^a, so that further description is unnecessary. It will be noticed, however, that the ducts 15^a, leading from the valve chambers 13^a are situated somewhat differently from the ducts 15 shown in Figure 1 in order that the tubes 9 leading to the secondary valvular devices can be easily inserted therein. The form of the double-acting valve 21^a is shown, by way of example, different to that of the corresponding valve 21 shown in Figure 1 and the cap-piece and bridge-piece are dispensed with, but it will be understood that the said valves could if desired be similar to those shown in the said Figure 1, and the cap-pieces and bridge-pieces be provided.

By casting or otherwise forming therein two or more valve chambers with their ducts in one base piece or block, as aforesaid, considerable economy in cost of manufacture is effected and moreover the blocks can be easily removed when it is required to have access to the diaphragms or passages leading to the purse pockets or to the suction channel in the suction board.

What I claim is:—

1. In pneumatically operated player mechanism for musical instruments, a valve block, a suction board attached to said valve block, and a pouch board interposed between said valve block and said suction board.
2. In pneumatically operated player mechanism for musical instruments, a valve block having therein valve chambers and a hollow cavity into which said valve chambers open, a suction board attached to said valve block, said suction board having passages therein,

in combination with a pouch board interposed between said valve block and said suction board, said pouch board having ports therein cooperating with the passages in said suction board and with the valve chambers in said valve block.

5 3. In pneumatically operated player mechanism for musical instruments, a valve block having valve chambers therein, valves in the 10 valve chambers, and a suction board attached to said valve block, in combination with a pouch board interposed between said valve block and said suction board, cap pieces constituting guides for said valves, and a bridge 15 piece serving to hold said cap pieces in place, substantially as described.

4. In pneumatically operated player mechanism for musical instruments a primary 20 valvular device for co-acting with a secondary valvular device, said primary valvular device comprising an auxiliary suction board secured to any suitable part of the instrument, a valvular block attached to said suction board, and a pouch board interposed 25 between said suction board and said valve block.

In testimony whereof I have signed my name to this specification.

ROBERT HENRY COLLEN.
